Patented Mar. 13, 1917.

UNITED STATES PATENT OFFICE.

EMILE WALDMEIER, OF GULFPORT, MISSISSIPPI.

AIR-REGULATOR FOR ENGINE-MANIFOLDS.

1,219,202.

Specification of Letters Patent. Patented Mar. 13, 1917.

Application filed April 30, 1915. Serial No. 24,868.

To all whom it may concern:

Be it known that I, EMILE WALDMEIER, a citizen of the United States, and a resident of Gulfport, in the county of Harrison and 5 State of Mississippi, have invented an Improvement in Air-Regulators for Engine-Manifolds, of which the following is a specification.

The present invention relates to gasolene 10 engines and more particularly to an auxiliary valve attachment associated with the carbureter thereof and adapted to automatically regulate the quality of the mixture being supplied to the cylinders.

15 The primary object of the invention is the provision of a device attached to the manifold of the engine and automatically operated by the inrush of air from the radiator and engine fan to increase or decrease the 20 amount of air intake to the mixture in conformity with the speed of the engine.

A further object is to provide an attachment of this character which may be applied 25 to engines of ordinary construction and which is durable, efficient in carrying out the purpose for which it is designed and inexpensive to manufacture.

The inventive idea involved is capable of 30 receiving a variety of mechanical expressions, some of which for the purpose of illustrating the invention, are shown in the accompanying drawing; but it is to be expressly understood that the particular construction shown in the drawing is used 35 merely to facilitate the description of the invention as a whole, and not to define the limits thereof, reference being had to the appended claims for this purpose.

40 In the drawing:— Figure 1 is a diagrammatic view of a gasolene engine showing the invention applied thereto.

Fig. 2 is an enlarged view of the device showing the same in its maximum open position.

45 Fig. 3 is a section taken substantially on the line 3—3 of Fig. 4.

Fig. 4 is an enlarged longitudinal section on the line 4—4 of Fig. 2, the parts being 50 shown in open position.

Fig. 5 is a view similar to Fig. 2, the device being shown in closed position, and

Fig. 6 is a transverse section on the line 6—6 of Fig. 4.

55 Referring more particularly to the accompanying drawing in which like reference

characters indicate similar parts, the numeral 10 indicates generally the engine, the same being provided with the usual engine fan 11, radiator 12 and manifold 13. The 60 carbureter 14 is secured to one end of the manifold as usual and between said carbureter and the cylinders of the engine the manifold 13 has mounted therein the auxiliary valve attachment which comprises the 65 essential feature of this invention.

The manifold 13 is provided with a threaded opening 15 into which projects the reduced externally threaded end 16 of a connection 17 the outer end of which is enlarged as indicated at 18 and also provided with external threads. An internally threaded cylinder 19 having an open inner end is threaded upon the enlarged portion 18 of the connection 17 and adjusted thereon 70 in any desired position.

The top of the cylinder 19 is enlarged as shown at 20 and has secured to this enlarged portion, by means of set screws 21, an angular bracket 22 having a depending portion 23 which extends in front of the outer end of the cylinder 19 and spaced a distance therefrom. The closed outer end of the cylinder 19 is provided with a centrally located opening in which is mounted a small bearing 85 pin 24 extending longitudinally of the cylinder 19 and having its ends pointed as shown. The depending portion 23 of the bracket 22 is provided with an opening, in alignment with the bearing pin 24, adapted 90 to receive an adjusting screw 25, the inner end of which forms a bearing for the adjacent pointed end of said pin. The cylinder 19 also has mounted therein a disk 26 which is adjustable longitudinally of said cylinder 95 and provided centrally thereof with an opening, in alignment with the bearing pin 24, adapted to receive a screw 27, similar to screw 25, the inner end of which engages the adjacent pointed end of the pin 24.

100 The portion of the pin 24 projecting beyond the outer end of the cylinder 19 has pivotally mounted thereon an oscillating plate 28 having an arcuate slot 29 therein which is adapted to register with a similar 105 slot 30 in the closed end of the cylinder 19 when the parts are in the position shown in Fig. 2. The air is then permitted to pass through said slots and openings 31 formed in the disk 26 and thence into the manifold 110 13 where it mixes with the original mixture from the carbureter 14. If desired a plu-

rality of spacing rings 32 may be inserted into the cylinder 19 between the outer end thereof and the disk 26. The oscillating plate 28 is adapted to abut the outer end of the cylinder 19 and is provided with a relatively large vane 33 the plane of which extends at right angles to the plane of said plate. A spring 34 is coiled about the inner end of the bearing pin 24 and has one of its ends secured in the cylinder 19 while the other end thereof is connected to a pin 35 which projects through the arcuate slot 30 in the cylinder 19 and has its outer end secured in the plate 28. This spring 34 is adapted to normally retain the vane in the position shown in Fig. 5 when the slots 29 and 30 are out of registry. It will thus be apparent that the vane 33 is moved toward the position shown in Fig. 2 against the tension of the spring 34.

In practice, when the engine is running at a normal or slow speed the inrush of air from the radiator 12 and engine fan 11 is insufficient to overcome the tension of the spring 34 and move the vane 33 to the opening position. However, when the speed of the car and engine is accelerated sufficiently to cause the pressure of air against the vane 33 to move the same toward the left, as shown in the drawing, the plate 28 will be oscillated about its pivot 24 until the arcuate slot 29 therein registers with the slot 30 in the cylinder 19 when air will pass therethrough into the manifold, as previously described. If the pressure of air against the vane is sufficiently strong the same will be moved to the extreme position shown in Fig. 2 where the movement will be limited by the engagement of the pin 35 with the adjacent end of the slot 30 and in this position the slots will be in complete registry. It will thus be seen that the amount of air passing through the valve into the manifold is regulated in conformity with the amount of pressure on the vane 33. As soon as the speed of the engine is decreased to normal the pressure on the vane will be relaxed and the same will return toward its normal position through the medium of the spring 34.

50 I claim:

1. In a device of the character described, the combination of a valve casing having means for direct attachment to the manifold of an engine or the like, a movable valve mounted upon the casing to control the inlet opening of the casing, and an air impact member comprising an elongated blade adapted to be actuated by air currents and directly secured at one end to said valve to actuate the latter.

2. In a device of the character described, the combination of a casing forming an air passage, and having means for connection to a manifold of an engine or the like, a valve 65 to control said passage, and an air impact

blade to be contacted and actuated by air currents and having an integral extension immovably fixed directly upon said valve to actuate the same.

3. In a device of the character described, 70 the combination of a casing forming an air passage having means of connection with a manifold, a valve for controlling the air through said passage, and an elongated swinging blade having at one end an integral offset part detachably mounted directly upon said valve to move therewith and adapted to be actuated by air currents from a fan or the like.

4. An attachment for intake manifolds or 80 the like comprising a casing having an opening, a rotatable valve to control said opening, a vane adapted to be actuated by air currents, said vane having an enlarged outer free end, and being directly connected at its 85 opposite end to said valve to actuate the latter, and spring means acting in opposition to the air currents.

5. An attachment for intake manifolds 90 comprising a cylindrical casing, one end wall of which has the means for attachment to the manifold and the opposite end wall of which has an inlet opening, a valve disk rotatably mounted upon said opposite end wall, an elongated blade adapted to be actuated by air currents directly secured to said valve, said valve having an opening adapted in the movement of said blade to register with the opening in said opposite end wall of the casing, and a bracket mounted upon the casing overlying the valve and having a bearing therefor.

6. An attachment for intake manifolds or 105 the like comprising a casing having an opening, a rotatable valve to control said opening, a vane adapted to be actuated by air currents, said vane being free at one end and directly connected at its opposite end to said valve to actuate the latter in one direction, spring means for actuating the 110 valve in an opposite direction, and a pin and slot connection between the valve and casing for limiting the movement of the valve and vane in opposite directions.

7. In a device of the character described, 115 the combination of two coöperating disk members, one of which constitutes a wall of an air chamber, which said wall has an integral screw threaded extension adapted to be connected to an intake manifold or the like, and the other of which disk members being mounted for oscillating movement, the said disk members having curved slots adapted in one of the relative positions thereof to register, and an elongated impact 120 blade carried by the last mentioned disk member adapted to be actuated by air currents to move the same.

8. In a device of the character described, 125 the combination of a casing forming an air

- chamber, and having means of attachment to an intake manifold or the like, a disk valve to control the admission of air into said chamber, and an impact vane adapted for moving the disk member in one direction, and an air impact vane mounted upon said disk and adapted to move the same in an opposite direction.
- 5 to be actuated by air currents, said vane having an integral offset end adapted to overlie one surface of the valve, retaining means for securing said offset part to the valve.
9. An attachment of the character described comprising a tubular member having an outer end wall adapted at its inner end for connection with a manifold or the like, said outer wall having an opening therein, a movable plate adapted to engage
- 10 the outer surface of said outer wall and having associated means for normally maintaining the same in position to close said opening, a vane mounted upon said plate and acting under pressure of air currents there-
- 15 20 against to move said plate whereby to expose said opening in the outer end wall and permit the entrance of air therethrough.
10. In a device of the character described, the combination of a tubular casing having
- 25 a rear end wall with a slot therein, a disk valve mounted upon the outer surface of said end wall and having a slot therein to coöperate with the slot of the casing, said disk valve having a central bearing where-
- 30 by the same may oscillate, spring means
- for moving the disk member in one direction, and an air impact vane mounted upon said disk and adapted to move the same in an opposite direction.
11. In a device of the character described, 35 the combination of a tubular wall having an outlet at one end for communication with a manifold or the like and a closed wall at its opposite end with an inlet opening therein, a rotatable disk valve having an opening 40 adapted to register with said inlet opening in the movement of said valve, an overhanging bracket secured to the periphery of the disk, a shaft for the valve having a bearing in the wall of the casing, an adjustable bearing on said bracket for the opposite end of said shaft, and an air impact member mounted upon said disk for actuating the latter.
12. In an internal combustion engine having an air circulating fan, the combination of an intake manifold having an inlet opening, a rotatable valve for said opening, and a vane secured directly to said valve and constituting in effect an integral extension 55 of the valve adapted to be actuated by air currents produced by said fan, to rotate the valve and regulate said opening.

EMILE WALDMEIER.
